UNITED STATES PATENT OFFICE.

LESTER BUDD, OF PHILADELPHIA, PENNSYLVANIA.

OPERATING DEVICE FOR SHAKING-GRATES.

1,395,478.

Specification of Letters Patent. Patented Nov. 1, 1921.

Application filed January 29, 1920. Serial No. 354,956.

To all whom it may concern:

Be it known that I, LESTER BUDD, a citizen of the United States, residing at Philadelphia, in the county of Philadelphia and 5 State of Pennsylvania, have invented certain new and useful Improvements in Operating Devices for Shaking-Grates, of which the following is a specification.

Large shaking grates for furnaces are 10 often made in sections and the sections are adapted to be individually rocked by an attendant. Very often the attendant after rocking or shaking one of the sections does not move the same back into its level position. In other words, the bars of the section 15 are permitted to remain in a tilted position and this is detrimental to the grate since it causes the quick burning out of the grate bars in view of the fact that the extensions 20 or edges of the bars are subjected to the heat of the fire bed and furthermore this action results in loss of fuel and heat.

One object of my present invention is to 25 compel an attendant to return the bars of each grate section to their normal level position before the bars of another section can be rocked.

Another object is to provide means for 30 preventing the accidental rocking or displacement of the bars of the sections from their normal positions.

A further object is to make the device 35 of my invention of a simple and durable construction and so that it can be practically connected to shaking grates of various types.

These objects, and other advantageous ends which will be described hereinafter, I attain in the following manner, reference being had to the accompanying drawings in 40 which—

Figure 1 is a side elevation showing my invention connected to a shaking grate in which two sections of the grate are illustrated; the bars of any one of the sections 45 being capable of being rocked independently of the bars of the other sections.

Fig. 2 is a fragmentary top plan view of the structure shown in Fig. 1,

Fig. 3 is a front elevation of the structure 50 shown in Figs. 1 and 2,

Fig. 4 is a section taken on the line 4—4 of Fig. 1,

Fig. 5 is a fragmentary sectional plan view taken on the line 5—5 of Fig. 1, and

Fig. 6 is a perspective view of one of the 55 elements of my invention.

Referring to the drawings, 7 represents a grate frame having a grate 8 mounted therein; said grate being illustrated as including two sections *x* and *y*; each section 60 having a number of rockably mounted grate bars 9. The grate bars have depending portions to which members 10 are pivotally connected and two shaking bars 11 and 12 are respectively connected to the grate bars 65 of the sections *x* and *y* through the medium of the members 10. These shaking bars extend through a slot 13 in the front of the frame 7, as clearly shown in Figs. 1, 2 and 3.

A bracket 14 includes sides 25 which are 70 spaced apart and connected at their rear by a back plate 15. The back plate 15 is bolted to the front of the frame 7. Plates or wings 16 and 17 are detachably secured to the sides 25 of the bracket. Two rocking 75 levers 18 and 19 are pivotally mounted between the plates 16 and 17 on a bolt 20; said bolt passing through the portion 15 and wings 16 and 17 as clearly shown in Fig. 4. Each of the rocking levers 18 and 19 has 80 a lower arm 21 and an upper arm 22. The lower arms are respectively connected to the shaking bars 11 and 12 and the upper arms 22 are positioned between the wings 16 and 17 above the portion 15. Each of 85 the plates or wings 16 and 17 has two lugs 23 which are spaced apart to provide a guideway 24 for a purpose hereinafter described. The lugs 23 project into the spaces between the plates 16 and 17. Each of the 90 plates 16 and 17 at its top has a yoked latch 26 pivoted thereto and capable of being swung into embracing position with the upper arm 22 of the adjacent rocking lever and these latches are operative to prevent 95 accidental movement of the rocking levers when the latter have been returned to their normal positions after having been operated to shake the respective grate sections.

A single hand-lever 27 has a recess 28 extending upwardly from its bottom; said recess being of the same contour as the upper arms of the rocking levers 18 and 19 so that when said hand-lever is slipped downward over either of the upper arms of the rocking 100 levers the latter will fit within said recess and the hand-lever can be moved to rock the levers 18 and 19 to effect the shaking of 105

the grate bars. The hand-lever 27 has projections 29 extending laterally in opposite directions from its opposite sides; said projections, when the rocking levers 18 and 19 are in their proper normal positions with their connected grate bars level, being capable of being slid through the guideway 24 between the lugs 23 adjacent either of the upper arms 22 of the rocking levers 18 and 19 to permit the attachment of the hand-lever 27 to either of the rocking levers. When the hand-lever is thus properly secured to either of the rocking levers, the projections 29, after having passed through the guideway 24, will be located at a level below the bottoms of the lugs 23 so that the rocking lever to which the hand-lever is attached can be actuated to cause the shaking of the grate section. However, it will be noted that the hand-lever 27 cannot be withdrawn from the rocking lever until the latter has been moved into a position in which the projection 29 on one side of the hand-lever is in alinement with the guideway 24 since in any other position, the lugs 23 will serve as a stop to prevent the hand-lever from being pulled off the rocking lever. Thus, after actuating one of the rocking levers, it is necessary to return the rocking lever to its normal and proper position with the grate bars level before the hand-lever can be removed from the rocking lever. In this manner, the attendant is compelled to return the bars of each section to their proper positions before he can remove the hand-lever for attachment to another one of the rocking levers.

When one of the rocking levers is to be actuated its embracing latch can be swung away therefrom to permit the attachment of the hand-lever and after the rocking lever has been actuated and brought back to its normal position the latch can again be swung

into embracing position with the rocking lever and thereby hold the lever against accidental movement.

While I have described my invention as taking a particular form, it will be understood that the various parts of my invention may be changed without departing from the spirit thereof, and hence I do not limit myself to the precise construction set forth, but consider that I am at liberty to make such changes and alterations as fairly come within the scope of the appended claim.

Having thus described my invention, what I claim as new and desire to secure by Letters Patent is:—

A device of the character described including a grate frame, a part secured to said frame and having an upwardly extending fixed side plate with two laterally projecting lugs spaced apart to provide a guideway therebetween; a pivoted grate-rocking lever having an arm movable in a plane to the side of and spaced from the ends of said lugs; and a removable operating lever having an end portion providing a socket adapted to slide over said arm, said portion of the lever having a projection adapted to move downwardly in said guideway between said lugs to a level below them, said arm extending to a position above said lugs to facilitate the application of said portion of the operating lever to said arm with said projection in alinement with said guideway, said lugs and projection preventing the removal of said operating lever when said projection is out of alinement with said guideway.

In testimony whereof I have signed my name to this specification in the presence of two subscribing witnesses.

LESTER BUDD.
